HARVESTER CAB

Lawrie G. McIntosh, Toronto, Ontario, Canada, assignor
to Massey-Harris-Ferguson Inc., Racine, Wis., a cor-
poration of Maryland

Application October 5, 1955, Serial No. 38,232

Term of patent 14 years

(Cl. D14—3)

Fig. 1

Fig. 2

Figure 1 is a right side elevational view of a harvester cab embodying my new design.

Figure 2 is a perspective view, on an enlarged scale, of the cab shown in Figure 1.

The harvester illustrated by means of broken lines is shown only for purposes of illustration.

I claim:

The ornamental design for a harvester cab, substantially as shown and described.
